US00D937796S

(12) **United States Design Patent** (10) Patent No.: **US D937,796 S**
(45) Date of Patent: **** Dec. 7, 2021**

(54) **TELEVISION RECEIVER**

(71) Applicant: **LG Electronics Inc.**, Seoul (KR)

(72) Inventors: **Younsoo Kim**, Seoul (KR); **Yooseok Kim**, Seoul (KR); **Hyoungwon Kim**, Seoul (KR)

(73) Assignee: **LG ELECTRONICS INC.**, Seoul (KR)

(**) Term: **15 Years**

(21) Appl. No.: **35/509,480**

(22) Filed: **Nov. 27, 2019**

(80) **Hague Agreement Data**

Int. Filing Date: **Nov. 27, 2019**

Int. Reg. No.: **DM/207588**

Int. Reg. Date: **Nov. 27, 2019**

Int. Reg. Pub. Date: **May 29, 2020**

(30) **Foreign Application Priority Data**

May 29, 2019 (KR) 30-2019-0025587

(57) **CLAIM**

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Back perspective view

1.9 : Exploded

1.10 : Another back perspective view of the television receiver shown in use with environmental cable wires connected

1.11 : Another back perspective view of the television receiver shown in use with a stand and environmental cable wires connected

The fine lines on the drawings indicate the curved surface or display part; the broken lines depict portions of television receiver or environment that form no part of the claimed design.

1 Claim, 11 Drawing Sheets
